US00D677743S

(12) **United States Design Patent**
Koshiishi

(10) **Patent No.:** **US D677,743 S**
(45) **Date of Patent:** **** Mar. 12, 2013**

(54) **ROBOT**

(75) Inventor: **Takeshi Koshiishi**, Saitama (JP)

(73) Assignee: **Honda Motor Co., Ltd**, Tokyo (JP)

(**) Term: **14 Years**

(21) Appl. No.: **29/416,676**

(22) Filed: **Mar. 26, 2012**

(30) **Foreign Application Priority Data**

Sep. 28, 2011 (JP) 2011-022187
(51) **LOC (9) Cl.** **21-01**

(52) **U.S. Cl.** **D21/578; D15/199**

(58) **Field of Classification Search** D21/578-583,
D21/621, 622; 446/268-274, 279, 280, 285,

(57) **CLAIM**

The ornamental design for, a robot, as shown and described.

DESCRIPTION

FIG. 1 is a first perspective view of a robot showing new design;

FIG. 2 is a second perspective view thereof;

FIG. 3 is a front elevational view thereof;

FIG. 4 is rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines are for environmental purposes only and form no part of the claimed design.
